SUCTION CLEANER

Charles H. Taylor, North Canton, Ohio, assignor
to The Hoover Company, North Canton, Ohio,
a corporation of Ohio

Application October 9, 1933, Serial No. 692,738

15 Claims. (Cl. 15—6)

The present invention relates to suction cleaners in general and particularly to a new and improved rotary agitator for a suction cleaner. More specifically the invention comprises the provision of a rotary agitator for a suction cleaner which is provided with positively actuated surface-contacting agitating elements for the purpose of increasing their cleaning effectiveness.

It is an object of the present invention to provide a new and improved suction cleaner. It is a further object to provide a new and improved rotary agitator for a suction cleaner. Still another object is the provision of a rotary agitator for a suction cleaner which includes surface-contacting agitating elements which are positively actuated relative to the body of the agitator. A still further object is the provision, in a suction cleaner rotary agitator, of surface-contacting agitating elements which are provided with an independent downward movement at the time of surface contact for the purpose of imparting a greater force to the covering undergoing cleaning. Another object is the provision of rigid beating elements in a rotary agitator for a suction cleaner which are movable radially in a definite sequence in the operation of the cleaner. Still another object is the provision of a rotary agitator which is provided with a surface-contacting brush which moves radially in a certain sequence in the cleaner operation. A further object is the provision of an improved rotary agitator for a suction cleaner which is provided with surface-contacting agitating elements which move radially relative to the body of the agitator, the agitator being adapted to function as a lip of the cleaner nozzle. These and other more specific objects will appear upon reading the following specification and claims and upon considering therewith the attached drawings to which they relate.

40 In the drawings, in which preferred embodiments of the present invention are disclosed:

Figure 1 is a side view, partly in section, of a modern suction cleaner with an agitator constructed in accordance with the present invention embodied therein;

Figure 2 is a side elevation of an agitator constructed in accordance with the present invention;

Figure 3 is also a side view of the agitator with certain parts broken away showing the interior mechanism thereof;

Figure 4 is a cross section upon the line 4—4 of Figure 3;

Figure 5 is an end view of the interior of the

cleaner nozzle constructed in accordance with a second embodiment of the invention;

Figure 6 is a partial top view of the end of the cleaner nozzle used with a second preferred embodiment of the present invention;

Figure 7 is a section upon the line 7—7 through the cleaner nozzle of Figure 5 showing the second preferred embodiment of the invention;

Figure 8 is a section upon the line 8—8 of Figure 7;

Figure 9 is a section upon the line 9—9 of Figure 7;

Figure 10 is a section through the agitator upon the line 10—10 of Figure 7;

Figure 11 is a view in perspective of one of the 15 positively actuated beating elements removed from the agitator;

Figure 12 is a partial cross-section through a suction cleaner nozzle, upon the line 12—12 of Figure 13, showing a third preferred embodiment 20 of the invention in which the agitator functions as the front nozzle lip;

Figure 13 is a bottom view of the construction shown in Figure 12;

Figure 14 is a partial longitudinal cross section 25 through the agitator constructed in accordance with the third embodiment of the invention;

Figure 15 is a section upon the line 15—15 of Figure 13;

Figure 16 is a view in perspective of the spring-holding element for the agitator brushes used in the embodiment shown in Figures 12 to 17, inclusive;

Figure 17 is a view in perspective of the brush spring.

Study of suction cleaner operation has disclosed that the amount of embedded foreign matter removed from a surface covering varies with the force of the beating blow delivered to the covering. Greater beating force is obtained through the use of rigid-contacting elements than by the use of brushes, and the force delivered by these rigid elements is also increased by raising the speed of rotation of the agitator on which they are positioned. The speed of rotation of the suction cleaner agitator is limited, however, by certain mechanical factors including pulley ratios, belt life and strength, and other elements. In an agitator constructed in 50 accordance with the present invention it is possible to increase the force of the blow delivered to the surface-covering undergoing cleaning without increasing the rotational speed of the agitator. This has been accomplished in 55

a new and novel manner as will be hereinafter fully disclosed.

Referring now to the drawings and to Figure 1 in particular, a suction cleaner with agitator constructed in accordance with this invention is disclosed. The suction cleaner is seen to comprise a nozzle 1 having surface-contacting lips 2 and 3. The nozzle is interiorly connected to the fan chamber 4 by means of the air passage-way 5 and within the chamber is positioned a suction-creating fan 6 carried by the lower end of the motor shaft 7 which is itself formed as a pulley 8 at its extremity. An exhaust outlet 9 is connected to the fan chamber 4 and opens 10 to a dust bag 10 which is removably held in place by means of manually operable nut members 11, of which one is shown. An unshown motor is housed within the casing 12, with the shaft 7 thereof extending downwardly as 15 described. The cleaner is movably supported upon a surface undergoing cleaning by means of spaced pairs of front and rear supporting wheels, there being one wheel of each pair shown in Figure 1 and indicated by the reference characters 13 and 14. Height-adjusting means 15 are connected to the rear wheels which enable those 20 wheels to be raised and lowered relative to the body of the cleaner for the purpose of raising and lowering the nozzle lips 2 and 3. A pivoted handle 16 is connected to the cleaner body and serves as means by which the operator can exert a propelling force, the incoming current leads 17, 17 extending along the handle to the motor casing 12.

Referring now to Figures 1 to 4 in particular, one preferred embodiment of the present invention is shown. The agitator is seen to comprise a body 20 which is elongated and cylindrical and which is provided substantially mid-way 40 of its length with a portion of reduced diameter 21 which functions as a pulley to receive the driving belt 22. The body 20 is rotatably supported upon the through supporting shaft 23, at least one end of which is made angular in cross 45 section to prevent the shaft rotating. An end cup 24 at each end of the body seats that member upon a bearing 25 which is carried by the shaft while a stationary thread-guard member 26 carried by the shaft overlies the ends of the 50 body to prevent the accumulation of hair, string and similar foreign matter about the bearing.

Removable brushes 27, 27 are seated in elongated channels or seats 28, 28 in the agitator body, each brush being removably seated with 55 the ends of its rigid back extended under the ends of the seat, a spring 29 in the bottom of the brush seat cooperating to hold the brush in that position.

Spaced circumferentially and longitudinally in 60 the body 20 are a series of radial channels or seats 30, 30 which are open at their bottom and face the supporting shaft. Within each seat 30 is a beater element 31 of a type commonly known as a rigid positive beating element. Element 31 is adapted to slide radially within its seat 30 relative to the agitator body, the head of the element being shouldered as at 32, 32 to limit its inward displacement under the force exerted by a coil spring 33 which is positioned 65 within the seat 30 and contacts an inner side of the member 31 and a transversely extending plate member 34 carried by the seat.

In the operation of the cleaner constructed in accordance with this embodiment of the invention, the rotation of the cleaner motor functions

to create a reduced pressure within the nozzle 1 and to lift the surface covering undergoing cleaning into the contact with the lips 2 and 3. The agitator being rotated under the force transmitted by the driving belt 22 rotates in contact with the surface covering and the brushes 27, 27 perform the usual brushing action. Each positive beating element 31 is held in its innermost radial position by its coil spring 33, the limiting position being that in which the shoulders 32, 32 contact the top of the element seat. The agitator is mounted in the cleaner nozzle with the shaft so positioned that the cam face which is formed thereon adjacent the seats 30 is arranged with its major axis pointing vertically, 10 or as shown in Figure 4 of the drawings. With the shaft so positioned upon the rotation of the agitator body relative thereto, the inner sides of the beater elements contact the sides of the stationary cam as they are rotated toward and approach their surface-contacting positions. As each beating element approaches its lowermost position, that is its point of surface contact, its inner side contacts the cam face of the supporting shaft and the element is forced radially outward against the force exerted by its coil spring 33. It is seen, therefore, that at the time of surface covering contact of each beating element the element is moving not only around the axis of rotation of the agitator, but also away 20 from that axis with a speed which is determined by the contour of the cam face. The force of the blow delivered by each beater element to the covering is seen to be increased by its radial speed, which is towards the surface covering at 30 the time of contact. After each beater element passes its lowermost point it is moved radially inward by its spring 33, the cam being shaped to permit such movement.

Referring now to Figures 5 to 11, inclusive, a 40 second preferred embodiment of the invention is disclosed. In this embodiment the improved cleaning action of the agitator is further increased by the provision of means which direct cleaning air to the point of surface contact at the 45 exact time of that contact. This desired result is obtained by interiorly connecting the agitator with the exterior atmosphere. To accomplish this result the end wall of the nozzle is apertured as at 35, the stationary thread-guard 26 and the 50 agitator end cup 24 being similarly apertured at 36 and 37, respectively. Spaced interfitting circular flanges upon the thread guard and the end cup form a labyrinth 38 which functions to substantially eliminate the passage of air around 55 each end of the agitator and directly into the nozzle. In the present embodiment each end of the supporting shaft 23 is carried in a plate 39 which is itself seated within an open bottom recess formed in the interior of the nozzle end wall, 60 screws 40, 40 removably holding the plate in place. Rotation of the agitator shaft is prevented as one of its ends is rectangular and seats within a rectangular opening in the end plate.

The beater elements 31, 31 etc. and their seats 65 30, 30 etc. are also modified in the present construction in that the seats are provided with side openings 41, 41 and in that the beater elements are provided with transverse openings 42, 42 so that the interior of the beater element is itself 70 open to the interior of the agitator and so to atmosphere. The aperture 42 in the beater element is so located that with the beater element positioned in its lowermost position, or that shown in Figure 10 of the drawings, air escapes from the 75

agitator body through the beater element to the exact point of surface contact. With a beater element in its inner radial position the opening 42 is within the element seat and substantially no air passes into the nozzle. As in the previous embodiment the beater elements are urged radially inward by coil springs and are forced radially outward in certain angular positions by the cam surface of the supporting shaft.

10 Referring now to Figures 12 to 17, inclusive, a third preferred embodiment of the invention is disclosed in which the agitator construction is so modified that it is capable of functioning as a lip of the nozzle which rotates in substantially sealed relationship with the adjacent stationary nozzle wall. This desirable relationship results in the cleaning air entering the nozzle passing between the agitator and its agitating elements and the surface covering. This relationship is made possible by providing an element-actuating cam which moves the beating element beyond the normal radial circumference of the agitator body during a limited angle of rotation only, both the rigid beating element and the flexible brush element being radially movable.

In this embodiment the agitator body and the actuated beating elements are constructed substantially in the manner shown in the embodiment found in Figures 1 to 4, inclusive. The supporting shaft 23 is non-rotatably supported in the present embodiment within a pivoted frame member 45 and is so positioned relative to the cleaner nozzle that it extends in substantially sealed relationship with the front wall thereof, a flexible agitator-contacting seal member 46 being provided which substantially prevents the passage of air between the agitator and the front nozzle wall. There is, in this embodiment of the invention, no stationary front nozzle lip, the rear nozzle lip 2 being positioned substantially as shown in the first embodiment. The beating elements 31, 31 etc. are mounted to move radially in their seats 30, 30 etc., as in the first embodiment, the cam formed on the supporting shaft 23 being so shaped that the radial movement of each element beyond the normal surface of the agitator body does not commence until that element has moved beyond the stationary front nozzle wall, the direction of rotation being as indicated by the arrow in Figure 15.

The brush 27 and its seat 28 in the agitator are both of modified construction in the present embodiment, the brush being adapted to slide radially in its seat in the manner of the rigid beating element, instead of being stationary therein as in the first embodiments. This relationship is desirable in order that the brush will not contact the stationary front nozzle wall as it rotates thereby. The movement of the brush is accomplished by providing a cam-contacting element 47 on the inner side thereof in such position that it is adapted to contact the cam 23 in the exact manner that the inner sides of the beater elements 31 contact that member. The brush is held in its innermost position, that position being determined either by the bottom of the brush seat or by the cam, by means of a spring 48 which is carried by a member 49 positioned on the interior of the agitator adjacent the brush seat. Spring 48 performs the same function for the brush that coil spring 33 performs for the beater element to which it is attached.

In the operation of this last described embodiment of the invention as the agitator is rotated in contact with the surface covering the

beater elements and the brush elements are moved radially outward relative to the agitator body as their cam-contacting portions contact the cam face provided on the supporting shaft. The cam on the shaft is so designed that the outward radial movement of any surface-contacting element does not begin until that element has passed by the front nozzle wall. The relationship of the nozzle wall and the agitator is such that cleaning air drawn into the nozzle by the reduced pressure existing therein is drawn under the rotating agitator to effect a maximum cleaning. The fact that the agitating elements are within the normal periphery of the agitator body when opposite the area of contact of that body with the nozzle wall and its seal permits a substantially air tight relationship to be obtained between the agitator and the wall resulting in substantially no leakage therebetween and a maximum air flow under the agitator which, in effect, is a rotating nozzle lip.

I claim:

1. In a suction cleaner, a rotary agitator including a surface-contacting agitating element, means to rotate said element to contact a surface covering undergoing cleaning, means mounting said element for movement perpendicular to the plane of the surface covering at the time of contact, and cooperative means to force said element on said last-mentioned means at the time of contact to increase the force of the beating blow.

2. In a suction cleaner, a rotary agitator including a body, means rotatably mounting said body, a surface-contacting element on said body, means mounting said element for radial movement relative thereto, and means to force said element radially outward relative to said body at the time of contact of said element with the surface covering undergoing cleaning.

3. A suction cleaner, a rotary agitator including a surface-contacting element, means rotatably supporting said element, means mounting said element for radial movement toward and from its axis of rotation, and means to move said element radially outward during a certain arc of rotation.

4. A suction cleaner, a rotary agitator including a surface-contacting element, means rotatably supporting said element, means mounting said element for radial movement toward and from the axis of rotation, and means to move said element radially outward during a certain arc of rotation, and means to return said element to an inner position.

5. In a suction cleaner, a rotary agitator including an elongated body, means rotatably mounting said body, a surface-contacting element, means mounting said element for radial movement relative to said body, and means to force said element radially outward relative to said body at the time of contact of said element with the surface covering undergoing cleaning, characterized by the fact that said element extends radially beyond said body in its outermost position and is substantially within the normal contour of said body in its inner position.

6. In a rotary agitator for a suction cleaner, a cylindrical body, a stationary shaft rotatably supporting said body, an agitating element mounted on said body for radial movement, a cam surface on said shaft, and cam-contacting means associated with said element to move said element radially upon rotation of said body.

7. In a rotary agitator for a suction cleaner, a

- cylindrical body, said body being provided with a radial seat, a stationary shaft extended thru and rotatably supporting said body, a cam surface on said shaft spaced radially from said seat, an agitating element slidably seated in said seat, cam-contacting means associated with said element, and spring means to urge said element radially inward, said cam-contacting means forcing said element radially outward during a certain arc of agitator rotation.
8. A rotary agitator for a suction cleaner including a cylindrical body, means rotatably mounting said body, a brush mounted on said body for radial movement, means to move said brush radially outward during a certain arc of rotation of said body, and means to return said brush to its initial position.
9. In a suction cleaner, a nozzle, suction-creating means connected to said nozzle, an agitator rotatably mounted in said nozzle including a body interiorly connected to atmosphere, a radially movable beater element mounted on said body, said body being provided with an opening adjacent said element to direct cleaning air to the point of beating, said element functioning to close said opening in certain positions, and means to actuate said element relative to said body.
10. In a suction cleaner, a nozzle, suction-creating means connected to said nozzle, an agitator including a body rotatably mounted in said nozzle, openings in the end of said body and in the adjacent nozzle wall interiorly connecting said agitator to atmosphere, means substantially preventing the passage of air into said nozzle at the ends of said body, a surface-contacting element seat in said body, an opening in said body at said seat connecting the interior of said agitator with said nozzle, a surface-contacting element mounted in said seat for radial movement, and means to move said element radially upon the rotation of said agitator, said element cooperating to open said opening when projecting from said body to deliver a beating blow and to close said opening when retracted into inoperative position.
11. In a suction cleaner, a nozzle, suction-creating means connected to said nozzle, an agitator including a body rotatably mounted in said nozzle, openings in the end of said body and in the adjacent nozzle wall interiorly connecting said agitator to atmosphere, openings in said body connecting the interior thereof with the nozzle, valves to open and close said openings, and means to move said valves to open position when said openings are positioned adjacent a surface covering undergoing cleaning.
12. The construction set forth in claim 11 characterized by the fact that said valves are beater elements and deliver beating blows to the covering while being moved to open position.
13. In a suction cleaner, a nozzle, suction-creating means connected to said nozzle, an agitator including a body rotatably mounted adjacent to and in sealed relation with a wall of said nozzle, an agitating element on said body adapted to move radially to project beyond said body in order to agitate a surface covering or to be retracted within the normal contour of said body, and means to actuate said element relative to said body during the rotation of the latter so that said element obtains its maximum projection when facing a surface covering undergoing cleaning and its minimum projection when facing the adjacent nozzle wall.
14. The construction set forth in claim 13 characterized by the fact that said agitating element is a rigid beating element.
15. The construction set forth in claim 13 characterized by the fact that said agitating element is a brush having flexible surface-contacting bristles.

CHARLES H. TAYLOR. 40
